UNITED STATES PATENT OFFICE

EDWIN HENRY ODENHEIMER, OF ALLENSTOWN, PENNSYLVANIA

ILLUMINATING DEVICE

Application filed April 2, 1928, Serial No. 266,635. Renewed August 21, 1930.

The present invention relates to improvements in illuminating devices, and has reference more particularly to a device for illuminating show windows and display signs therefor.

One of the important objects of the present invention is to provide an illuminating device of the above mentioned character which is simple in construction, inexpensive, strong and durable, and further well adapted to the purpose for which it is designed.

Other objects of the invention will become apparent as the nature of the invention proceeds and when taken in connection with the accompanying drawings.

In the accompanying drawings, forming a part of this application and in which like numerals designate like parts throughout the several views:

Figure 1 is a vertical sectional view through a show window showing my improved illuminating device suspended from the ceiling thereof, the illuminating device being shown in end elevation.

Figure 2 is a front elevation of the illuminating device suspended in a show window.

Figure 3 is a vertical sectional view through the illuminating device.

Figure 4 is a fragmentary top plan view thereof.

Figure 5 is a fragmentary rear elevation.

Figure 6 is an enlarged fragmentary sectional view, for more clearly showing the manner in which the lower edge of one of the reflectors engages with an annular flange and extends inwardly from a light emitting opening formed in the inclined rear portion of the bottom wall of the casing.

Figure 7 is a fragmentary front elevation of the illuminating device, the glass panel being partially removed.

Figure 8 is a detail of the socket for supporting each reflector, showing the manner

in which the same is suspended from the top of the casing, and

Figure 9 is a diagrammatic view of the wiring system for the electric lamps forming a part of the present invention.

In the drawings, wherein for the purpose of illustration is shown the preferred embodiment of my invention, the numeral 1 designates generally my improved illuminating device, the same comprising a substantially rectangular shaped casing that is constructed of suitable metal, the same including spaced end walls 2, a rear wall 3, a top wall 4, and a bottom wall 5, the front side of the casing being opened. An inwardly directed flange 6 extends around the forward edges of the end walls as well as the top and bottom, and suitable strips 7 are arranged on the inner opposed faces of the top and bottom, inwardly of the flange 6 to provide a guide for receiving and supporting a glass panel 8 that is slidable through a slot formed in one end of the casing.

Arranged on the glass panel is any suitable advertising matter adapted to be illuminated by suitable electric lamps arranged in the casing 1, in a manner to be presently described.

The glass panel is removable, for interchanging purposes, so that glass panels containing different advertising matter may be arranged in the open front side of the casing as desired.

The rear portion of the bottom 5 of the rectangular casing is inclined upwardly as shown at 9, in Figures 3 and 6 of the drawings and manifestly, the lower rear edge portions of the end walls 2 are cut away to conform to the upwardly inclined rear portion 9 of the bottom wall 5 of the casing.

Formed in the inclined portion 9 of the bottom 5 at spaced intervals are the light emitting openings 10, and an annular flange is formed around each opening and is dis-

posed upwardly for disposition within the casing. The purpose of the flange 11 around each of the openings will be herein-after more fully described.

5 A tubular member 12 has its upper end threaded for disposition through a suitable opening provided therefor in the top 4 directly over each of the openings 10 and suitable nuts 13 are threaded on the upper threaded end of each of these pipes for engagement with the respective sides of the top 4 to securely hold the pipe and this feature is more clearly disclosed in Figure 8 of the drawings.

15 An insulating light supporting socket 14 is adjustably supported on the lower portion of each pipe 12 and to this end the upper portion of the socket is formed with a collar 15 and a set screw 16 extends radially through the collar for engagement with the pipe to secure the socket member on said pipe.

20 An electric lamp 17 is associated with each socket 14 and a reflector 18 is secured at its upper end on the lower portion of each socket unit 14, through the medium of the attaching ring shown at 19, in Figure 3. The reflectors 18 are preferably formed of glass having a reflective coating on their 25 interior to render the same opaque, but it is to be understood that said reflector may be of any suitable material. The lower portion of the reflector is disposed in angular relation with respect to the upper portion of the 30 reflector and the lower edge of the reflector extends around the inwardly directed flange 11, in the manner as shown very clearly in Figure 6, so that the light will be projected downwardly and rearwardly to illuminate 35 the rear portion of the show window.

40 Additional lamp sockets 20 are secured in the upper portion of the casing to the top 4 for disposition between the aforementioned sockets 14, and these sockets 20 receive the lamps 21 which provide a means for illuminating the glass panel 8 that covers the open front side of the casing, and on which glass panel is printed or otherwise arranged suitable advertising matter.

45 The wiring for the several lamps is concealed within the channel shaped housing 22, that extends longitudinally across the upper face of the top 4, directly above the several sockets.

50 The wiring for the lamp is indicated at 23, and as clearly shown in Figure 9, all of the lamps are connected up together in series. The wiring extends through one end of the channel shaped housing 22 and has a conventional light socket plug 24, arranged on the extremity thereof for attachment to an electric light socket provided in the show window.

55 The casing is suspended from the ceiling 60 of the show window by suitable suspension

chains 25 and said casing may be suspended at any suitable height and is preferably arranged adjacent the front of the show window.

65 If desired, the illuminating device may be arranged in any desired position in the show window for the two-fold purpose of illuminating the show window and at the same time displaying an illuminated sign for the window.

70 An illuminating device of the above mentioned character may be manufactured at a very low cost and the same will, at all times, be positive and efficient in carrying out the purposes for which it is designed.

75 While I have shown the preferred embodiment of my invention, it is to be understood that minor changes in the size, shape, and arrangement of parts may be resorted to, without departing from the spirit of the invention and the scope of the appended claims.

80 Having thus described by invention, what I claim as new is:

85 1. An illuminating device of the class described comprising a rectangular casing open at its front side, a sign supported in the open front side of the casing, the bottom of the casing being formed with light emitting openings, electric lamps arranged within the casing, and reflectors completely housing certain of said lights to project rays of light only through the openings in the bottom of the casing, the other lights in the 90 casing illuminating the sign.

95 2. An illuminating device of the class described comprising a substantially rectangular shaped casing open at its front side, the rear portion of the bottom of the casing being inclined upwardly and formed with a series of spaced light emitting openings, an annular flange extending upwardly around each opening, a sign for the front open side of the casing, a plurality of electric lamps arranged in the casing, a reflector open at its lower end for disposition around the annular flange of each opening in the inclined portion of the bottom of the casing, said reflectors inclosing certain of the lamps to project the rays of light 100 through the openings in the bottom of the casing in a downward and rearward direction, the other lamps in the casing being adapted to illuminate the sign.

105 3. An illuminating device of the class described comprising a substantially rectangular shaped casing open at its front side, the rear portion of the bottom of the casing being inclined upwardly and formed with a series of spaced light emitting openings, an annular flange extending upwardly around each opening, a sign for the front open side of the casing, a plurality of electric lamps arranged in the casing, a reflector open at its lower end for disposition around 110

the annular flange of each opening in the inclined portion of the bottom of the casing, said reflectors inclosing certain of the lamps to project the rays of light through the openings in the bottom of the casing in a downward and rearward direction, the other lamps in the casing being adapted to illuminate the sign, and means for suspending the casing in a show window.

10 In testimony whereof I affix my signature.

EDWIN HENRY ODENHEIMER.
